AIR CONDITIONER

Arthur E. Kline and Wendell H. Webster, Albion, Mich., assignors, by mesne assignments, to McGraw-Edison Company, a corporation of Delaware

Application April 6, 1953, Serial No. 346,918

12 Claims. (Cl. 62—129)

This invention relates to air conditioning apparatus and more particularly to the type of air conditioning apparatus designed to be mounted in a window of a building and to occupy minimum space within the room so as not to project beyond the window sill.

In the use of window type air conditioners, it has been found necessary to arrange the parts comprising the units in compact form to carry and support the same as self-contained portable structures in the openings of the windows. Due to the requirement of compactness, the arrangement of the parts was not as simply carried out in design as might be desired to secure minimum protrusion from the window sill. This protrusion of the air conditioner units has been a real objection although very little effort has been made to decrease the depth of the units to eliminate this objection. As a result, most structures protrude unduly beyond the window sill into the room and are not only unsightly due to their bulkiness, but occupy valuable space within the room.

It is an object of the present invention to provide a new and improved air conditioning structure of the self-contained window type that will occupy minimum space within the room and preferably project into the room a distance no greater than the depth of the window sill.

It is a further object of the present invention to provide a new and improved air conditioning structure of the self-contained window type that will not only project into the room a distance no greater than the depth of the window sill, but a distance outwardly no greater than the normal for a device of this type.

It is a further object of the invention to provide a new and improved air conditioning structure of the self-contained window type that incorporates therein improved forms of fan construction for both the evaporator and condenser units whereby the depth of the air conditioning structure can be decreased to a point never obtained heretofore for the same capacity of air conditioning structure.

Further objects and advantages of the invention will be clearly apparent from the following detail description when taken in connection with the accompanying drawings which form a part thereof.

In the drawings:

Figure 1 is a perspective view of a window opening and air conditioning unit embodying the present invention, one side of the window frame being omitted and the wing board and attaching members being shown in exploded position;

Fig. 2 is a transverse section of a window frame illustrating in dotted lines the approximate area occupied by an air conditioning unit embodying the present invention,

2

it being understood that this occupied area is in relation to the window shown and that it may vary according to the construction of the window;

Fig. 3 is a top view with the housing removed of an air conditioning unit embodying the present invention;

Fig. 4 is a front view of the same with the housing removed;

Fig. 5 is a side view also with the housing removed;

Fig. 6 is a transverse section taken along line 6—6 of Fig. 3 looking in the direction of the arrows and illustrating the condenser fan and unit in elevation;

Fig. 7 is a transverse section taken along line 7—7 of Fig. 3 looking in the direction of the arrows and illustrating in front elevation the fan of the evaporator unit;

Fig. 8 is a section taken along line 8—8 of Fig. 3 looking in the direction of the arrows;

Fig. 9 is a detail elevational view of the damper door and its mounting controlling the flow of air so as either to recirculate the air in the room, to supply fresh air from the outside, or to exhaust the air from the room;

Fig. 10 is a top view partly in section and illustrating the position of this damper door at the time of providing either one of the aforesaid three positions;

Fig. 11 is an elevational view of one face of the fan for the condenser unit;

Fig. 12 is a top elevational view of the same taken along line 12—12 of Fig. 11 and looking in the direction of the arrows;

Fig. 13 is a sectional view taken along line 13—13 of Fig. 11 and looking in the direction of the arrows;

Fig. 14 is a fragmentary detail view of a portion of the condenser fan after the cutting operation but before the bending operation of the blades thereof;

Fig. 15 is a front elevational view of the fan for the evaporator unit;

Fig. 16 is a top elevational view thereof;

Fig. 17 is a transverse section taken along line 17—17 of Fig. 15 and looking in the direction of the arrows; and

Fig. 18 is a similar view but taken along line 18—18 of Fig. 15 and looking in the direction of the arrows.

As shown in the drawings, an air conditioning unit embodying the present invention comprises a base 10 adapted to receive a housing 11 having a front cover 12 detachable at 13. Cover 12 is provided with a grille panel 14 having openings 15 therein through which air from the room is drawn and passed through a filter 16 which will be accessible for replacement when hinged panel 17 is opened. Panel 17 is carried by front cover 12 and has therein a series of openings 18 through which cooled air is discharged into the room.

A control panel 19 having a series of knobs 20, 21 and 22 is conveniently disposed at the front so that upon the opening of hinged panel 17, these knobs will be readily accessible for operation. Knob 20 operates a damper 23 controlling the flow of air through an opening designated generally as 24 in Figs. 3 and 10. Damper 23 is so mounted that it may be moved to one of three positions by knob 20.

It will now be shown how manual rotation of control knob 20 effects positioning of circulation controlling valve or damper 23 in positions A, B or C. Note in Fig. 5 that knob 20 is journaled for rotation in panel 19 and that said knob carries a beveled gear 100 on the side of the panel opposite the knob. Gear 100 is meshed with an-

other beveled gear 101 which is rightly carried on a crank shaft 102 extending downwardly and terminating in a free end 103 which passes loosely through a slot 104 in bracket 105 affixed to damper 23. Hence, it is evident from examining Figs. 5, 9 and 10 that rotation of crank shaft 102 through the agency of knob 20 will cause free end 103 of the crank shaft to reciprocate in slot 104 so that bracket 105 will swing in a horizontal plane and damper 23 will alternatively swing on its left main hinge 107 or its right main hinge 109 so as to assume positions C and B, respectively (see Fig. 10).

The damper assembly is of unusual construction in that it enables swinging door 23 through its opening 24 in partition 99 from either edge thereof. In Figs. 9 and 10 will be seen that there are really a pair of identical but opposite hinges, for example, one includes a pair of main hinges 109 which are merely hooks extending through slots in partition 99 adjacent opening 24. A strap 109' extends across door 23 from main hinge 109 and terminates in an auxiliary hinge 110 which is in fact a hooked end formed on 109' to wrap around the edge of damper door 23. The second hinge is similar and it constitutes corresponding parts including a main hinge 107, a strap 107' and an auxiliary hinge 108.

If it is desired to operate damper 23 to position B for example, see Fig. 10, crank shaft 102 must be turned clockwise. This will cause free end 103 of the crank shaft to act on damper bracket 105 causing the latter to assume the dotted line position as shown in Fig. 10. Strap 109' will continue to lie against damper 23 but the damper will swing inwardly on hooked main hinge 109 and on auxiliary hinge hook 108. Opposite main hinge 107 will remain substantially stationary during this event although damper door 23 will swing inwardly away from strap 107'.

The same sequence of events takes place when crank shaft 102 is turned counterclockwise when viewed from the top. Damper door 23 would, of course, swing to position C on main hinges 107. It may be noted that door 23 is provided with a pliable sealing sheet 112 bonded to the inner face thereof by any well known means; air leakage is thereby prevented for all of the three positions A, B and C. When damper 23 is in the position shown in full lines or position designated A in Fig. 10 and closing opening 24, air in the room is merely recirculated by passing it through the conditioner in the order of grille 14, evaporator unit 27 and out again through upper hinged panel 17 (see Figs. 1 and 3). When damper 23 is in the dotted line position indicated at C in Fig. 10, fresh air is drawn through a screen-covered opening 26 in a portion of the side of housing 11 that projects beyond the window and outside of the room. This fresh air is then drawn through opening 24 and moved through filter 16 and over evaporator coils 37 disposed in the rear of filter 16, which coils 37 are a part of the evaporator unit designated broadly as 27. This air continues its movement by virtue of evaporated fan 28 into the chamber 28' of this evaporator fan and then upwardly through a passage 29 and moves forwardly through an opening 30 having a series of louvers 31 for directing the flow through openings 18 in outer hinged panel 17. Partition 32 houses evaporator fan 28 within this chamber 28' and the passage 29 and thus confines the currents of air by fan 28, which is of the centrifugal type and will be more fully explained later.

On the other hand, if damper 23 is in the dotted line position indicated at B in Fig. 10, air is exhausted from the room to the outside by reason of its movement through an opening 33 in a partition 34 extending diagonally from the side wall of housing 11 which has the screen protected opening 26 exposed to the outside. With damper 23 in position B, fresh air from the outside cannot be drawn through opening 26. However, a condenser fan 38, to be more fully described later, draws air through arcuate screen 26', opening 33, opening 24 and the room opening

15 in panel 14 in the front of housing 11. The air from the room is, therefore, partly moved through these openings and taken by condenser fan 38 through condenser coils 40 of the condenser unit designated broadly as 41. It will be understood, of course, that a portion of the room air is also circulated through filter 16 and over evaporator coils 37 by evaporator fan 28 which then circulates it forwardly through openings 30 and 15 and into the room in a cooled, filtered and dehumidified condition.

Both the evaporator fan 28 and the condenser fan 38 are driven by a motor 43 disposed between the same and mounted upon a bracket 44 secured to a raised portion 45' in base 10. Motor shaft 45 carries these fans at opposite ends, the arrangement being that minimum space is occupied by the parts so that the evaporator unit 27 and the condenser unit 41 may be disposed as closely together as possible upon base 10 with the motor 43 spaced therebetween.

The refrigeration apparatus includes the usual hermetically sealed motor compressor 46 carried by spring mountings 47 extending upwardly from base 10. The refrigerant is circulated in a closed system by this latter unit through the evaporator unit 27 and the expanded gases are then passed through the condenser unit 41. It will be understood that the refrigeration apparatus is standard equipment and that it is not a part of the present invention. The bottom or base 10 is formed to provide a well or depressed area 48 directly below the evaporator unit 27. This well 48 connects by a channel 49, see Fig. 3, with another well or depressed area 50 below the condenser unit 41. The condensate forming on evaporator coils 37 will drain into well 48 and will flow by way of channel 49 to well 50. The condenser unit 41 is disposed in an enclosure including top wall 51, side wall 52 and a partition 53, the latter having a central opening 54 into which condenser fan 38 projects (Fig. 8). Partition 53 extends down to the floor of well 50, but it is provided with an opening at 55 in one corner (Fig. 6) to permit the condensate to flow around this partition 53 into well 50. If the condensate is sufficient, it will rise to a level above the lower edge of a slinger ring 60 carried by and rotatable with condenser fan 38.

Slinger ring 60 will pick up the condensate and throw it against the condenser coil 40, effecting evaporation thereof. This evaporation increases the efficiency of condenser coil 40 because this evaporation tends to lower the temperature which aids the cooling action and the vapor is discharged therefrom to the outside. From the description thus far, it will be apparent that the parts of the air conditioning apparatus disclosed herein are compactly arranged.

It will be observed, however, that the design of both fans directly becomes a part of the general arrangement effecting such compactness decreasing the depth of the apparatus that when the apparatus is mounted in a window opening as illustrated in Figs. 1 and 2, the front face 61 of cover 12 is substantially flush with the edge of the sill 62 and there is no overhang or protrusion into the room as heretofore experienced. Without in any way decreasing the capacity of the apparatus, we have been able to reduce the depth, say, to twenty-two inches, which is considerably below the dimensional requirements structurally for devices heretofore of the same capacity.

Condenser fan 38, as shown in detail in Figs. 11 to 14, is preferably formed from a single sheet of material. It is provided with a plurality of blades 65 shaped so that their length is in the neighborhood of one-fourth of the diameter of the fan. With slinger ring 60 integrally formed about the fan's periphery, each blade 65 is then formed by punching out holes 66 and 67 in the body 68 and by making an incision 69 between these holes and defining the outline or outer edge of the blade. Forming tools are then used to press the material between these holes and within the incision outwardly into the shape

of each blade, it being noted that certain of these forming tools engage at points 70 and 71 (Fig. 14) to press inwardly while the blade is pressed outwardly or, relatively speaking, in the opposite direction. The outer edge 72 of each blade (Fig. 11) then extends outwardly or away from the fan body while the inner edge 73 extends outwardly slightly beyond the plane of the fan body but in the opposite direction. The material lying between a straight line extending from hole 66 to hole 67 and incision line 69 of the next blade becomes the axis of each blade as it is formed, and, as a novel consequence, the inner edge 73 moves beyond the plane of the fan body in a direction opposite to the blade itself and its outer edge 72. Hence, a portion of each blade 65 extends outwardly from the slinger ring 60 on opposite sides, which, to a certain degree, tends to minimize the depth of condenser fan 38.

As shown in Figs. 3 and 8, the curved portions of blades 65 extend from slinger ring 60 on the side opposite to condenser coil 40 and only slightly beyond the hub 76 and thus lying almost within the vertical plane of this hub. The opposite edges 73 of blades 65 project only a small distance from the slinger ring 60. The currents of air drawn by these blades 65 pass through the openings 77 between the blades and are produced by virtue of the blades being cut out of the fan body itself. It will also be noted that the blades 65 are continuous in their positioning about the fan and that no dead material is left between the blades. This provides a maximum effective blade surface for the space occupied by the blades without decreasing the capacity and eliminates the requirement of large blades of the propeller type that heretofore needlessly occupied space and contributed to awkward design and the projection of the air conditioning units a considerable distance into the room from the window sill. Moreover, the slinger ring 60 is uniquely arranged in a simple manner as noted in Fig. 8 to pick up condensate in well 50 and to distribute it into the air stream by throwing the condensate against the slanting side wall 52 of partition 53 forming a part of the condenser fan shroud and also against the slanting distributing flange 52' extending across and above the fan, and thence upon condenser coils 40 for evaporation and the added cooling thereof which will result from such evaporation. Fig. 8 very clearly shows the compactness resulting from the narrow depth of condenser fan 38. Central web portion 78 is reinforced by ribs 79, the formation of this web portion providing a strong central structure carrying hub 76.

Evaporator fan 28 carried upon the same fan shaft 45 is disposed just inside partition 32. It comprises a single vertical or back wall 80 and a plurality of blades 81 and 82 projecting laterally therefrom. Blades 81 have webs 83 extending radially inwardly to connect with a hub 84 while webs 85 of blades 82 stop short of the hub and do not connect thereto. The webs connect with their blades in a manner to produce a centrifugal type of fan which will draw currents of air to it at the central portion and which then permit the blades to force the currents of air centrifugally from the periphery. It will be noted that the back wall 80, the blades 81 and 82, their webs 83 and 85 and the hub 84 are molded as a single piece. The molding may be of any suitable material and it is mentioned that a plastic such as high impact styrene, an acetate or methyl methacrylate may be used, although any plastic with suitable stability and high impact value may be substituted. The construction of this fan 28 permits it to be very compactly disposed between the evaporator coil unit and back partition 32 and occupy minimum space without decreasing the capacity to circulate and cool the room air, or to exhaust air or add fresh air at the same time.

The air conditioning unit is shown mounted in a window opening in Figs. 1 and 2, and, as previously explained, the unit rests upon the sill 62 and may be carried so that the front face 61 is approximately flush with the edge of

the sill without protrusion therebeyond into the room. It will also be noted that the rear portion designated broadly as 90 extends outwardly of the room and the window opening the same distance as at the present time for the same capacity of unit. The usual side window shields 91, window shield brackets 92 and top window seal gaskets 93 are employed to seal the unit in the window frame, the usual base mountings (not shown) also being employed to carry the unit in position.

Without further elaboration, the foregoing will so fully explain the character of our invention that others may, by applying current knowledge, readily adapt the same for use under varying conditions of service, without eliminating certain features, which may properly be said to constitute the essential items of novelty involved, which items are intended to be defined and secured to us by the following claims.

We claim:

1. In a window type of air conditioner, a combination of parts effecting a compact unit projecting inwardly of a window substantially equal to the depth of a normal window sill and outwardly of the window of a depth not exceeding the normal of a device of this type comprising an evaporator unit, a condenser unit and a refrigerant circulating system for the two units, a fan for each unit, and means to drive the fans, the fan of the evaporator unit being of a centrifugal type with its blades projecting laterally from a single mounting wall carried by a hub to secure a reduced depth for said evaporator fan, a chamber for said evaporator fan including a partition wall adjacent the free ends of said centrifugal fan blades and having an aperture concentric with the axis of said fan communicating with said evaporator unit, said partition wall also having an outlet opening aligned with the outer periphery of said centrifugal fan blades for expelling air drawn through said aperture, a baffle interposed between said evaporator unit and said outlet opening the fan of said condenser unit having a series of propeller blades of a length substantially in the neighborhood of one-fourth the diameter of the fan to secure a reduced depth for said condenser fan.
2. In an air conditioning unit, a housing having two compartments, each provided with inlet and outlet means to permit passage of air therethrough, a refrigeration system including an evaporator mounted in one of said compartments and a condenser mounted in the other compartment, means including an evaporator fan adapted to circulate air in heat exchange relationship with the evaporator and to discharge such air into a room, means including a condenser fan adapted to circulate air in heat exchange relationship with the condenser and to discharge such air outside the room, a third compartment in said housing disposed along one of the outside walls of said housing, said outside housing wall having an opening therein to supply outside air to said third compartment, said third compartment having two additional openings therein, one of said openings leading to said evaporator fan and the other opening leading to said condenser fan, a three-position valve member, said valve member comprising a door, a pair of oppositely directed substantially U-shaped arms supporting said door, the free ends of said arms hingedly engaging opposite margins of the door and the closed ends of said arms being hinged respectively on opposite sides of the opening leading to said evaporator fan, and means to shift said valve member into any one of said three positions to close off either of said two additional openings or said outside opening either to recirculate the room air by said evaporator fan without outside air mixed therewith or with outside air mixed therewith or to exhaust the room air to the outside by said condenser fan.
3. In an air conditioning unit, a housing having two compartments, each provided with inlet and outlet means to permit passage of air therethrough, a refrigeration system including an evaporator mounted in one of said

compartments and a condenser mounted in the other compartment, means including an evaporator fan adapted to circulate air in heat exchange relationship with the evaporator and to discharge such air into a room, means including a condenser fan adapted to circulate air in heat exchange relationship with the condenser and to discharge such air outside the room, a third compartment in said housing, said third compartment being disposed along an outside wall of said housing with an opening therein to supply outside air to said third compartment, said third compartment having two additional openings therein, one of said openings leading to said evaporator fan and the other opening leading to said condenser fan, a valve member located in said third compartment at the intersection of said three openings and a single means to operate said valve member into any one of three positions to close off any one of the three said openings either to recirculate the room air by said evaporator fan without outside air mixed therewith, or with outside air mixed therewith, or to exhaust the room air to the outside by said condenser fan.

4. In an air conditioning unit, a housing having two compartments, each provided with inlet and outlet means to permit passage of air through a refrigeration system including an evaporator mounted in one of said compartments and a condenser mounted in the other compartment, means including a centrifugal evaporator fan located in alignment behind said evaporator and adapted to circulate air in heat exchange relationship with the evaporator and to discharge such air into a room, means including a condenser fan adapted to circulate air in heat exchange relationship with the condenser and to discharge such air outside the room, said outlet means of said evaporator compartment including a grilled opening above said evaporator in the front of said housing, a chamber at the rear of said grilled opening, and a baffle separating said evaporator compartment from said chamber, whereby warm air flows in one direction into said evaporator coil beneath said baffle and in an opposite direction out of said outlet chamber above said baffle.

5. An air conditioning unit comprising a housing, a condenser compartment having outlet means and inlet means leading to the interior of said housing, an evaporator fan compartment spaced from and parallel with said condenser compartment, said evaporator fan compartment being open at the top and imperforate to air flow into said housing interior, a propeller fan extending into said condenser inlet means and a centrifugal fan in said evaporator fan compartment, a motor disposed within said housing interior and carrying each of said fans on opposed ends of its shaft in immediate adjacency to said motor, an evaporator compartment having an outlet aperture communicating with said centrifugal fan and an inlet opening, a chamber connected with said evaporator compartment through said inlet opening, said chamber being substantially coextensive with the height of said evaporator compartment and having a top closure defining the bottom of the passageway for the discharge from said centrifugal fan, a partition within said housing having an outside air inlet opening, an opening to said chamber and an opening to said housing interior, damper valve means disposed at the intersection of the pathways leading to said last three named openings, single control means for actuating said damper means to close one of said three openings, whereby closing said opening to said chamber places the outside air opening in communication with the interior of said housing, and closing said interior opening admits outside air to said chamber and whereby closing said outside opening causes said condenser fan to exhaust room air through said chamber opening and said housing interior.

6. In an air conditioner of the type having a compartment with a heat adsorbing element therein, a compartment with a heat dissipating element therein, an air inlet and outlet to and from each compartment, air circulating

means for circulating air from an enclosure to be cooled and ambient air from outside the enclosure through the compartments having a heat adsorbing and heat dissipating element, respectively, the combination with such an air conditioner of selective means for independently exhausting stale air from or adding outside ambient air to the enclosure comprising an open passageway communicating with the enclosure and the outside ambient, said passageway having ports communicating with the separate compartments at the suction side of the air circulating means, and a single movable damper mounted in the passageway to either close the port from the passageway to the compartment having the heat dissipating element and open the passageway or open said port and close the passageway between said port and the outside ambient.

7. An air conditioner in accordance with claim 6 in which the single movable damper is mounted in the passageway to close the port from the passageway to the compartment having the heat dissipating element or close the passageway on either side of said port.

8. An air conditioner in accordance with claim 6 in which the single movable damper is mounted to close the passageway between ports in one position, close the port from the passageway to the compartment having the heat dissipating element in another position to cause outside air to flow in one direction through the passageway to the suction side of the compartment having the heat adsorbing element, or close the passageway between said port to the compartment having the heat dissipating element and the outside ambient in another position to cause air from the enclosure to flow in the opposite direction through the passageway and port to the suction side of said compartment.

9. An air conditioner in accordance with claim 6 in which said port from the passageway to the compartment having the heat dissipating element constitutes an outside air inlet and the passageway constitutes a bypass around said port to the air inlet to the other compartment when said port is closed by said damper.

10. An air conditioner in accordance with claim 6 in which the passageway constitutes a bypass around the air inlet to the compartment having the heat absorbing element when said damper is adjusted to open the port from the passageway to the compartment having the heat dissipating element and close the passageway between said port and the outside ambient.

11. In a room air conditioner of the type having a compartment with a heat absorbing element therein through which a stream of room air is circulated in a predetermined path and an adjacent compartment with a heat dissipating element therein through which a stream of outside air is circulated in a predetermined path, the combination with such a room air conditioner of a port opening between the compartments, a single damper for closing the port opening in one position and movable to a plurality of other positions, and said port opening and damper being so constructed and arranged with respect to the paths of the air streams in the different compartments as to induce the flow of outside air through the port opening into the room in one of said plurality of positions and induce the flow of room air through the port opening to the outside in another of said plurality of positions.

12. An air conditioner having a housing divided into adjacent compartments, a refrigeration system having a heat absorbing element in one compartment and a heat dissipating element in the adjacent compartment, each of said compartments having an air inlet and outlet, means for circulating room air and outside air through the respective compartments, a passageway between compartments, a damper having at least one vane for closing the passageway and movable to a plurality of other positions, said damper in one of said plurality of other positions opening a path from the air inlet to one compartment to the passageway and baffling the flow of air from the passageway to the outlet from said compartment, and

said damper in another of said plurality of other positions closing the path from the air inlet to the passageway and opening a second path from said passageway to the air outlet from said compartment.
